UNITED STATES PATENT OFFICE

ORVAL R. PLATTER, OF NORTH VERNON, INDIANA

DESIGN FOR A CANOPY SETTEE

Application filed January 5, 1931. Serial No. 38,203. Term of patent 3½ years.

To all whom it may concern:

Be it known that I, ORVAL R. PLATTER, a citizen of the United States, residing at North Vernon, in the county of Jennings and State of Indiana, have invented a new, original, and ornamental Design for Canopy Settees, of which the following is a specification.

The accompanying drawing which is made a part hereof is a perspective view of a canopy-settee showing my new design.

I claim:

The ornamental design for a canopy-settee as shown.

In witness whereof I have hereunto set my hand and seal at North Vernon, Indiana, this 29th day of December, A. D. nineteen hundred and thirty.

ORVAL R. PLATTER.
